SLEEPING BAG

James L. Clark, New York, N. Y.

Application January 6, 1944, Serial No. 517,280

5 Claims. (Cl. 5—343)

My invention relates to improvements in sleeping bags.

Among its essential objects are to provide a unitary sleeping bag capable of being adjusted to suit varying temperature conditions; the provision of a changeable sanitary sheeting disposed contiguous to the occupant; a bag to encase not only the body but the head, if desired, with appropriate means for protecting the head against the elements and at the same time maintaining access to the outside for breathing; a sleeping bag entered with ease and also admitting of immediate egress therefrom should an emergency arise; and other features lending themselves to simplicity, efficiency of operating, and economy of manufacture.

Briefly described, the bag comprises an outer casing, an inner mattress and sanitary sheeting, assembled together to form a unitary sleeping bag, capable of adjustment to meet different temperature conditions and equipped with a flap for protection of the occupant's face and head and means for securing the flap.

To the accomplishment of the recited objects and others coordinate therewith, one embodiment of my invention resides in the construction and arrangement of parts hereinafter described, illustrated in the accompanying drawings and embodied in the scope of the appended claims.

In said drawings:

Fig. 1 is a perspective view of the assembled sleeping bag with the flap closed.

Fig. 2 is a similar view of the bag with the flap in open position.

Fig. 3 is an enlarged fragmentary perspective illustrating details of the head end of the assembly.

Fig. 4 is a detail top plan of the obverse side of the sheeting in opened position.

Fig. 5 is a similar view of the reverse side of the sheeting.

Fig. 6 depicts a top plan of the opened inner mattress.

Fig. 7 is a similar illustration of the outer casing in opened position, and

Fig. 8 is an enlarged cross-sectional view of the sleeping bag taken along lines 8—8 of Fig. 2.

As shown in the drawings, the sleeping bag assembly comprises three principal elements: the outer casing 5, inner mattress 6, and sheeting 7, each shown in opened position in Figs. 7, 6 and 4 respectively.

The outer casing 5, as depicted in Fig. 7, in opened position, is preferably of balloon and cheese cloth construction, and has incorporated

therein feathers or down, or other comparable insulating material 51, see Fig. 8. The casing, which may be also designated as an outer mattress or shell, is folded longitudinally to present an upper fold 8 and a lower fold 9, the latter having an extension flap 10 of the same width as the body of fold 9.

Longitudinal edges 12 of fold 8 and 13 of fold 9, and the foot edges 14 and 15 of both folds of the casing are adapted to carry complementary parts 16 and 17 of a slide fastener, or other equivalent means, as best seen in Fig. 3. Immediately adjacent and paralleling the slide fastener components are weather strips 18—19 which contain the same type of insulating filler as the casing, and, as illustrated in Fig. 8, are designed to form an effective seal when the bag is closed.

Upper fold 8 may be slit lengthwise as at 20, with tapes 21 fastened thereto for closing the said slit if desired. In addition, loops 22 are stitched to flap 10, with tie tapes 23 at the upper extremities thereof, and tie tapes 24 also attached to the casing, as indicated in Fig. 7.

In conjunction with the outer casing, inner mattress 6, shown in opened position in Fig. 6, is employed. This member, when set up with casing 5 and sheeting 7, is also folded longitudinally to define folds 25 and 26, with fold 25 having its upper edge slit as at 27 to coincide with slit 20 of casing 5. Mattress 6 carries no slide fasteners, snaps or buttons at its marginal edges; however, loops 28 and tapes 29 are fastened thereon to hold this member in proper relation with respect to the other parts of the sleeping bag.

It has been found expedient and a safeguard to cleanliness to use sanitary sheeting 7, illustrated in Fig. 5. In outline, this sheeting conforms to the outer casing, with the exception that folds 30 and 31 thereof have at their upper ends companion flaps or pockets, 32—33, the latter adapted to receive and cover flap 10 of the outer casing, and the former designed to cover the upper terminals of folds 8 and 25 of casing 5 and inner mattress 6. Flap 33 is a folded flap bound at the sides to produce a pocket. Sheet 7 also carries tie tapes 34 and is slit at 35 as indicated in Fig. 4. Tie tapes 36 are fastened to the corners of flap 32, while the corners of flap 33 are cut away as at 37 to receive loops 22 and to permit tapes 23 of flap 10 to be drawn therethrough making for facile assembly of the sleeping bag.

Referring particularly to Figs. 2, 3 and 8, the outer casing 5, inner mattress 6 and sheeting 7 are assembled by means of the various tapes and loops; the units are then folded together; and

slide fastener parts 16 and 17 of casing 5 are closed, thus securely fastening the otherwise open side and bottom of the bag, leaving the head end open for access of the occupant. It will be noted that in this stage, sheeting 7 covers all portions of the bag which may contact the body, head and face of the occupant.

In mild temperatures, the inner mattress 6 (Fig. 3) may be removed entirely or folded under sheeting 7, using only upper fold 8 of the outer casing 5 and fold 30 of the sheeting 7 as a covering.

In extreme cold, further protection to the head and shoulders is furnished by flap 10, which may be drawn over the head, face and shoulders of the occupant and adjusted to suit. It may be positioned by tucking the flexible edges of flap 10 over and around the head and under the flexible edges of the upper mattress assembly. Or it may be loosely held by the hand or hands holding tie tapes 23 or by the same tie tapes being passed under the sheeting tie tapes and drawn taut but left untied, for a friction hold. With the flap 10 thus arranged, quick exit from the bag may be had by merely "pushing" the flap from the face and head, dragging the unfastened tie tapes 23 from the sheeting tie tapes 36.

The occupant may leave tapes 21 untied and use the slit, provided in each of the upper folds of the members. This slit serves as an aperture for the face, while the two sides cuddle the face and shoulders in a manner not ordinarily possible.

With my sleeping bag the occupant may rest in comfort on his back or turn from side to side without rolling the entire bag or disturbing the general adjustment of flap 9. One may breathe easily the outside atmosphere through a suitable channel arranged along the lower edge of the flap. Furthermore, because of the inherently flexible nature of the flap, it may be adjusted to suit an occupant of any height.

Eminently satisfactory results are obtained by use of my sleeping bag; economy of manufacture; the health of the occupant may be safeguarded by changing or cleaning the sanitary sheeting.

In its broader aspects the invention comprises not only the various means described but equivalent means for performing the recited functions.

It is desired to reserve the right to effect such changes and modifications as may come fairly within the scope of the appended claims.

I claim:

1. A sleeping bag assembly comprising an outer casing folded longitudinally forming a laterally folded lower and an upper leaf with the foot, one side and the top of said casing open when the casing is in folded position, the lower leaf provided with a full width extension flap for covering the head and face of an occupant, an inner mattress having similar laterally folded leaves encased within and secured to said outer casing and a sheeting having a shape similar to said outer casing and being similarly folded to provide a laterally folded lower end and an upper leaf, said sheeting lying between the folds of said mattress and covering the same, the upper ends of said leaves having pocket portions extending therefrom, the pocket portion of the lower leaf of the sheeting covering the extension flap of the lower

leaf of the outer casing and the pocket portion of the upper leaf of the sheeting covering the upper terminals of the upper leaf of the casing and the upper leaf of the mattress and means attached to the outer casing for closing the foot and one side of the casing when the bag is assembled.

2. A sleeping bag assembly comprising, in combination, an outer casing folded longitudinally forming a laterally folded lower and an upper leaf with the foot, one side, and the top of said casing open when the casing is in folded position, the lower leaf provided with a full width extension flap for covering the head and face of an occupant, an inner mattress folded longitudinally forming laterally folded leaves and encased within said casing, a sheeting having a laterally folded lower and an upper leaf similar to the leaves of the casing and encased therein, said leaves having pockets extending therefrom, said pockets covering respectively said flap of the casing and the upper terminals of one of the leaves of the casing and one of the leaves of the mattress and means to hold the members in assembled relation.

3. A sleeping bag of the type defined in claim 2, in which the head ends of the upper portions of the outer casing, mattress and sheeting are provided with corresponding slits, and means to close the same.

4. A sleeping bag having an outer casing folded longitudinally forming a lower and an upper portion with the foot, one side, and head end of the casing open, the lower portion having a flap extension, an inner mattress encased within the outer casing and folded longitudinally to form a lower and an upper portion, the inner mattress adapted to be removed from and inserted into the casing, a sheeting inserted between the folds of said mattress, said sheeting being folded longitudinally to form a lower and an upper portion, said portions having pockets adapted to cover respectively the extension flap of the lower portion of the casing and the upper terminals of the upper portions of the casing and the mattress, and means to close the open side and foot of the casing, leaving the head end open.

5. A sleeping bag assembly comprising an outer casing folded longitudinally forming a laterally folded lower and an upper leaf, the lower leaf being provided with a full width extension flap for covering the head and face of an occupant, an inner mattress having similar laterally folded leaves encased within and secured to said outer casing, and a sheeting having a shape similar to said outer casing and being similarly folded to provide a laterally folded lower and an upper leaf, said sheeting lying between the folds of said mattress and covering the same, the upper ends of said leaves having pocket portions extending therefrom, the pocket portion of the lower leaf of the sheeting covering the extension flap of the lower leaf of the outer casing, and the pocket portion of the upper leaf of the sheeting covering the upper terminal of the upper leaf of the casing and the upper leaf of the mattress, and means to hold the members in assembled relation.

JAMES L. CLARK.
